(57) **CLAIM**

The ornamental design for a bottom roller of a wafer toggle roller as shown and described.

DESCRIPTION

1. Bottom roller of a wafer toggle roller

FIG. 1.1 is a front perspective view of a bottom roller of a wafer toggle roller showing my new design

FIG. 1.2 is a front view thereof;

FIG. 1.3 is a rear view thereof;

FIG. 1.4 is a left-side view thereof;

FIG. 1.5 is a right-side view thereof;

FIG. 1.6 is a top view thereof;

FIG. 1.7 is a bottom view thereof; and

FIG. 1.8 is another front perspective view showing the design in a state of use.

The broken lines in the drawing figures depict portions of the bottom roller of a wafer toggle roller that form no part of the claimed design.
